UNITED STATES PATENT OFFICE.

ALBERT LION, OF BALTIMORE, MARYLAND, ASSIGNOR TO EPHRIAM ROSENFIELD, GEORGE M. HARSH, AND NOAH DILLENBERG, A PARTNERSHIP KNOWN AS E. ROSENFIELD & CO., OF BALTIMORE, MARYLAND.

NECKBAND.

1,032,554.

Specification of Letters Patent.

Patented July 16, 1912.

Application filed October 25, 1911. Serial No. 656,687.

To all whom it may concern:

Be it known that I, ALBERT LION, a citizen of the United States of America, residing at the city of Baltimore, State of Maryland, have invented certain new and useful Improvements in Neckbands, of which the following is a specification.

This invention relates to a neck band.

The object of the invention is to produce 10 a neck-band having an end pocket which will serve to protect the wearer from the base or back of the collar button, and is at the same time so constructed that it does not appreciably increase the difficulty of inserting 15 the collar button.

A further object is to so design the neck-band and to evolve a method of producing it whereby it will be possible to manufacture the shirt at a cost very slightly in excess 20 of the cost of those which do not have the neck-band end pocket.

The pocket of my invention in its preferred type is open top and bottom. The neck strip proper, which is reinforced on 25 the inside by a suitable tab, forms one side of the pocket, and one or two or more reinforcing neck strips sewed together as hereinafter described, form the other side of the pocket. The reinforcing tab is turned in 30 top and bottom, and the neck strip is turned in at the top throughout its length and at the bottom, for the length of the tab only, and the inturned edges, where they contact, are sewed together; the reinforcing neck 35 strips are turned in at the top, and the inturned top edges of the neck strip and reinforcing strips are sewed together. The ends of the tab and the neck strip are sewed between the ends of the reinforcing neck 40 strips. The edges of the ends of the latter are inturned and sewed to secure the ends of all the different strips. A buttonhole is worked in the end of the neck strip where reinforced by the tab. The neck band thus 45 formed may be attached to the shirt in any suitable and obvious manner.

The neck-band pocket thus described may be produced by each of several methods. The method which I prefer to practise, is 50 as follows: I first apply to one end of the neck strip a short tab sewing it at the top and bottom edges, leaving the ends open; I then turn the tube thus formed inside out, and make the buttonhole in the rein-

forced strip thus formed. Next I apply 55 to each side of the neck strip a reinforcing neck strip, and sew the top and end edges of all the neck strips together. The seam thus formed does not engage the top edge of the tube or reinforced strip which I 60 have described. The reinforcing neck strip on the side of the neck-band, remote from the reinforcing tab, is then turned away from the neck strip proper and folded over against the neck strip proper so that the 65 band which I formed by sewing the top edges of all three neck strips together is in effect turned inside out and the top edge is seamed and the bottom sewed to the neck opening of the shirt. 70

By another method of manufacture which is within the scope of my invention, the reinforcing tab is attached to the neck-band by sewing it directly thereto, the edges being hemmed or inturned as they are sewed. In 75 this case, the tube thus formed is not turned inside out. The other steps of the method, i. e., those relating to the application of the reinforcing neck strips are the same as the corresponding steps in the method which 80 I have described.

In the production of another neck strip within the scope of my invention, the reinforcing tab is extended the full length of the shirt band, forming a third reinforcing neck 85 strip.

The neck band formed in accordance with my invention and the various steps of my method are illustrated in the accompanying drawing. 90

Figure 1 is a fragmentary view of the end of a neck-band to which the reinforcing tab has been attached in accordance with the first step of my preferred method. Fig. 2 shows a similar view of the neck-band after 95 the tube formed by the strip illustrated in Fig. 1 has been turned inside out. Fig. 3 shows the end of the neck-band, in which the pocket is formed, the reinforcing strips having been applied and stitched at the top 100 and end. Fig. 4 shows the neck-band after the reinforcing strip, which finally becomes the inside strip, has been folded over in accordance with the fourth step of my method. Fig. 5 shows the end of a neck strip to 105 which the reinforcing tab has been sewed at top and bottom, in accordance with the first step of the second method to which I

have referred. Fig. 6 shows another embodiment of my invention. Fig. 7 is a section on the line 7, 7 of Fig. 4. Fig. 8 is a section on the line 8, 8, Fig. 4.

5 In the drawings, the neck strip proper is indicated by reference character 1, the reinforcing tab by reference character 2, and the buttonhole is numbered 3. The buttonhole is preferably of the kind known in the art as 10 whipped, that is, it is overcast from the inside, and it thus tends to remain open and does not become closed by the treatment it receives at the laundry.

By examination of Fig. 4 it will be noted 15 that the top edge 4 of the reinforced end 5 of the neck-band is somewhat lower than the top edges of the united reinforcing neck strips 6 and 7; this renders the pocket more easy of access for inserting the collar button.

20 The end pocket which I have described affords desirable protection for the neck against the base of the collar button, and the buttonhole 3 constructed so that it will remain open, and it has the edge 4 lower 25 than the back edge 8, and the bottom edges 9 of the band 5 above the seam 10, which attaches the band to the shirt. It is, therefore, easy of access. Further, it is preferably open top and bottom.

30 The device shown in Fig. 6 differs from the others in that instead of the tab 2, I have used a strip 11 running the full length of the neck-band. All these devices are for use with an attached or detached collar.

35 The method which I prefer to practise in the manufacture of my neck-band consists in sewing the top and bottom edges of the reinforcing tab to the top and bottom edges of the neck strip proper 1, the seams being

40 numbered 15 and 12 second turning the tube inside out, third applying the reinforcing

neck strips 6 and 7, one to each side of the neck strip proper 1, sewing the top and end edges of the strips thus assembled at 13 and 45 14, leaving the top edge 4 of the reinforced end 5 free, fourth swinging the reinforcing neck strip 7 over the neck strip proper 1, and bringing it down against the inside face of the reinforcing neck strip 6. This process is so simple and convenient that it may 50 be performed with great rapidity, and when it is practised the cost of the garment having the end pocket in the neck-band is not appreciably greater than that of the garment not so improved.

55

Having thus described my invention, what I claim and desire to secure by Letters Patent is:

A neck-band for shirts, and other garments, having a front pocket for the stud base at one end of the band, the pocket being open top and bottom and closed at the end, a neck strip and reinforcing member forming one side of the pocket, and reinforcing neck strips forming the other side of the pocket, the latter strips being turned inward at the top and having the inturned edges sewed together, and the neck-band and the reinforcing member being likewise turned in at the adjacent top and bottom edges and 60 sewed together, the end of the neck strip proper being inserted between the ends of the reinforcing strips, and the end edges of the latter being turned in and sewed together, securing the end edge of the neck-band between the end edges of the reinforcing neck bands.

75

Signed this 23rd day of October, 1911.
ALBERT LION.
